UNITED STATES PATENT OFFICE.

FRANCIS K. MOSELEY, OF OWENSBORO, KENTUCKY.

GROOMING DEVICE.

No. 799,799.

Specification of Letters Patent.

Patented Sept. 19, 1905.

Application filed March 11, 1905. Serial No. 249,632.

To all whom it may concern:

Be it known that I, FRANCIS K. MOSELEY, a citizen of the United States, residing at Owensboro, in the county of Daviess and State of Kentucky, have invented a new and useful 5 Grooming Device, of which the following is a specification.

This invention relates to grooming devices; and it has for its object to simplify and improve 10 the construction and operation of this class of devices.

With these and other ends in view, which will readily appear as the nature of the invention is better understood, the same consists in the improved construction and novel 15 arrangement and combination of parts, which will be hereinafter fully described, and particularly pointed out in the claims.

In the accompanying drawings have been 20 illustrated simple and preferred forms of embodiment of the invention, it being understood that no limitation is necessarily made to precise structural details therein exhibited, but that the right is reserved to any changes, 25 alterations, and modifications to which recourse may be had within the scope of the invention and without departing from the spirit or sacrificing the efficiency of the same.

In said drawings, Figure 1 is a perspective 30 view of a grooming device constructed in accordance with the principles of the invention. Fig. 2 is a transverse sectional view taken on the line 22 in Fig. 1. Fig. 3 is a sectional detail view taken on the plane indicated by the line 33 in Fig. 1. Figs. 4 and 5 are detail views illustrating modifications.

Corresponding parts in the several figures are indicated throughout by similar characters of reference.

40 This improved grooming device while partaking in some respects of the nature of a brush adapted especially to operate upon the limbs of a horse is also in the nature of a massage implement for the purpose of reducing 45 swollen limbs and for preventing the same, for the purpose of removing wind-galls, and for other purposes which will readily suggest themselves.

The improved grooming device may be 50 briefly described as consisting of a strap 1 of flexible material—such as textile fabric, rubber, leather, or the like—said strap being provided at each end with a handle 2, whereby it may be conveniently manipulated, and said 55 strap being furthermore provided on one side thereof or on both sides, if preferred, with

a plurality of transversely-disposed or other suitably-arranged rubbing members, the nature of which may be considerably varied.

A simple form of the device illustrated in 60 Figs. 1, 2, and 3 of the drawings shows a strap made of textile material, such as duck, said strap being provided with folded and overlapping edges 33, as best seen in Fig. 2, so as to form a flattened tube. An auxiliary 65 strap 4 of similar material is secured by stitching or in any other suitable manner upon the tubular strap 1 in such a manner as to form a plurality of flutings or pockets 55, which constitute the rubbing-surface. The 70 handles 2, secured at either end of the device, may be composed of tubular strips of material, as 6, containing grip-pieces 7, of wood or other suitable material, and having their ends secured by stitching, as 8, in the ends of the 75 tubular strap member 1.

A grooming device of this extremely simple construction possesses numerous advantages which will be readily understood by practical horsemen. For the purpose of grooming the 80 limb of an animal it is extremely convenient, the operator being enabled to manipulate the strap which partially encircles the limb of the animal with great rapidity and with excellent results. The flutings 55 are flexible, and 85 yet somewhat stiff material will constitute a superior rubbing-surface. Hair and dirt will work in between the flutings, from which it may afterward be easily removed by simply shaking the device, and the side of the strap un- 90 provided with flutings or projections may be utilized for finishing the operation. For preventing and reducing swollen limbs as well as for the purpose of removing wind-galls this device will be found extremely convenient, 95 owing to the facility and convenience as well as the rapidity with which it may be operated to give the parts operated upon a thorough massage.

Under the modification illustrated in Fig. 4 100 the rubbing-surface is formed by strips 10 of material such as leather, secured by stitching transversely upon the strap 1. Under another modification illustrated in Fig. 5 strips 11, secured transversely upon the strap 1, which 105 is in this instance represented as being composed of a single thickness of material, are provided with bristles 12, which may be of any desired stiffness and which will of course constitute a very effective rubbing-surface. 110

It will be evident from the foregoing that this invention is capable of being modified in

numerous ways without departing from the spirit thereof, and I desire it to be understood that the strap which constitutes the base of the device may be of any appropriate material and may consist of one or more thicknesses; that the handles may be of any desired construction and may be connected with the said base in any suitable manner; that the rubbing-surface may consist of integral strips either of solid material or fluted or tubular or they may be provided with bristles, and that said strips constituting the rubbing-surface may be disposed transversely, diagonally, or in any other suitable and convenient manner.

Having thus described the invention, what is claimed is—

1. A grooming device comprising a flexible strap, handles at the ends of said strap, and a fluted rubbing member secured upon the latter.

2. A grooming device comprising a tubular flexible strap and an auxiliary flexible strap, said straps being connected at intervals and

the auxiliary strap being fluted between the points of connection.

3. A grooming device comprising a pair of flexible straps suitably connected at intervals, one of said straps being fluted between the connecting points.

4. A grooming device comprising a tubular strap, tubular flexible handle members having their ends secured in the ends of the tubular strap, and grip-pieces in said tubular handle members.

5. A grooming device consisting of a flexible strap, and rubbing members secured transversely upon said strap in parallel relation one to another.

In testimony that I claim the foregoing as my own I have hereto affixed my signature in the presence of two witnesses.

FRANCIS K. MOSELEY.
